DRILL MOUNTING STAND

Eugene W. Buck, Campbell, Calif., assignor of
one-third to Antonio Cano, Santa Clara, Calif.

Application September 2, 1952, Serial No. 21,286

Term of patent 14 years

(Cl. D63—1)

To all whom it may concern:

Be it known that I, Eugene W. Buck, a citizen of the United States, residing at Campbell, in the county of Santa Clara and State of California, have invented a new, original, and ornamental Design for a Drill Mounting Stand, of which the following is a specification, reference being had to the accompanying drawing, forming a part thereof.

Fig. 1 is an elevational view, looking at one side, of a drill mounting stand showing my new design; the dotted outline indicating a supported drill, which is for illustrative purposes only.

Fig. 2 is a similar view, but looking at the opposite side of the drill mounting stand.

Fig. 3 is a front elevation of the drill mounting stand.

Fig. 4 is a sectional plan view on line 4—4 of Fig. 2.

I claim:

The ornamental design for a drill mounting stand, as shown.

EUGENE W. BUCK.
